UNITED STATES PATENT OFFICE.

LUDWIG LÖWY, OF DUSSELDORF, GERMANY, ASSIGNOR TO SCHLOEMANN AKTIEN-
GESELLSCHAFT, OF DUSSELDORF, GERMANY, A CORPORATION OF GERMANY.

HYDRAULIC TUBE PRESS.

Application filed March 25, 1926, Serial No. 97,251, and in Germany September 2, 1925.

My invention has reference to hydraulic presses for the manufacture of seamless tubes. In presses of this type, the metal from which the tubes are formed, is pressed 5 or extruded while hot through a narrow annular space produced between a matrix and a piercing mandrel, which latter, while the hot metal is being extruded by a large press-plunger, is likewise moved in the direction 10 of the extrusion. The large press-plunger is usually made hollow, and within this hollow press-plunger is concentrically arranged the piercing mandrel, which projects backwardly from the large press-plunger and is 15 guided in a cylinder also provided back of the large press-plunger, where it is rigidly mounted. A drawback of this arrangement is the length of the piston carrying the piercing mandrel which greatly increases 20 the cost of such presses because of the considerable difficulty experienced in the manufacture and the machining of the long piston, which must be very exactly made and must also be very strong so as to withstand 25 the considerable bending strains to which it is subjected.

The object of the present invention is to eliminate these difficulties which I accomplish by providing both the member carrying 30 the piercing mandrel and the guiding member in the large hollow press-plunger, whereby the length of the member carrying the piercing mandrel is considerably shortened, so that special provisions to prevent 35 bending can be dispensed with. Moreover, the guiding faces are lengthened, the member carrying the piercing mandrel is moved with greater exactness, and because of the decreased wear, the life of the press is considerably increased. The piercing mandrel 40 can be carried either by a movable cylinder, guided by a stationary piston, or it may be carried by a movable piston guided by a stationary cylinder. In the latter case, the length of the press can be still further shortened, so that a very compact construction is 45 obtained.

For a more detailed description of my invention, I refer to the appended drawing, 50 in which Fig. 1 is a central sectional view showing an hydraulic press constructed in accordance with my invention; Fig. 2 is a like view showing a modification.

In all the figures, 1 designates the block 55 of hot metal received in the container 2,

while 3 designates the forward end of the large hollow press-plunger 4, which is guided in the cylindrical casing 5. 6 is the piercing mandrel, which in passing through a hole in the forward end 3 of press-plunger 4 pierces the hot mass of metal 1 and together with the matrix 7 forms a narrow annular space, through which the hot metal is extruded to form a seamless tube indicated 60 in all the figures at 8. 65

According to Fig. 1 illustrating one embodiment of my improved hydraulic press, the piercing mandrel 6 is provided at the forward end of a hollow plunger 15 which is guided within the large press-plunger 4 as well as by a stationary piston 16, extending 70 into the hollow plunger 15 within the large press-plunger 4. The other end of the stationary piston 16 is secured in the cross-head 17 of a standard 18, mounted on the hydraulic cylinder 5. Compared with the well-known press, the presses according to my invention as shown in Fig. 2 is considerably shorter and the relatively movable parts, that is to say, the member (hollow 75 cylinder 15) carrying the piercing mandrel 6 and the guiding member (piston 16) can be made considerably lighter.

In the modification shown in Fig. 2, the construction is still shorter and more compact than that shown in Fig. 1. According to Fig. 2, the piercing mandrel 6 is provided at the forward end of a movable piston 19 provided within the large press-plunger 4 and guided within a sleeve 20 secured in the bottom of the hydraulic cylinder 5 and extending into the press-plunger 4. The end of piston 19 is provided with a head 21, whereby the piston is guided within 80 said sleeve 20. 85

The operation of the press either as shown in Fig. 1 or in Fig. 2 is obvious. After the block 1 of hot metal has been placed in the container 2, the forward end 3 of the press-plunger 4 is moved toward the left in Figs. 1 and 2 so as to lightly bear against block 1. Thereupon, the member carrying the piercing mandrel 6 (i. e. cylinder 15 in Fig. 1 or piston 19 in Fig. 2) is moved so that the piercing mandrel will pass through the block 100 1 of hot metal determining the inner diameter of the tube 8 and forming with the matrix 7 a narrow annular space through which the hot metal is extruded by the gradual further advance of the forward end 3 105 110

of press plunger 4, while at the same time, the piercing mandrel 6 is also moved in the direction of extrusion. After all the metal has been extruded, firstly the piercing mandrel is withdrawn and when the residue of the metal has been expelled, the press plunger is moved back to its original position.

While I have thus described my invention in detail, I do not, of course, limit myself to the exact construction as shown, which may be varied, without a departure from the scope of my invention.

I claim:

15 1. In a hydraulic press for making seam-

less tubes, a plunger, a piercing device having a mandrel, and means for operating said piercing device independently of the plunger comprising a relatively movable piston and cylinder, said cylinder slidably engaging 20 the plunger.

2. In a hydraulic press for making seam-
less tubes, a plunger, a piercing device having a mandrel, and means for operating said piercing device independently of the plunger 25 comprising a cylinder slidably engaging the plunger, and a piston within the cylinder operatively connected to the piercing device.

In testimony whereof I affix my signature.

LUDWIG LÖWY.
